DESIGN FOR A JEWELRY FINDING FOR CHAINS OR THE LIKE

Paul F. Volk, Warwick, R. I., assignor to Carl-Art, Inc., Providence, R. I., a corporation of Rhode Island

Application January 23, 1939, Serial No. 82,525

Term of patent 7 years

To all whom it may concern:

Be it known that Paul F. Volk, a citizen of the United States residing at Norwood, in the county of Kent and State of Rhode Island, has invented a new, original, and ornamental Design for Jewelry Finding for Chains or the like, of which the following is a specification, reference being had to the accompanying drawing, forming part thereof.

In the drawing:

Fig. 1 is a front view of a jewelry finding for chains showing my new design;

Fig. 2 is a back view thereof; and

Fig. 3 is a section on line 3—3 of Fig. 1.

I claim:

The ornamental design for a jewelry finding for chains or the like, as shown.

PAUL F. VOLK.
